UNITED STATES PATENT OFFICE.

ROMAIN DE TIRTOFF, (ERTÉ), OF PARIS, FRANCE, ASSIGNOR TO W. H. & A. E. MARGERISON & CO., OF PHILADELPHIA, PENNSYLVANIA, A FIRM COMPOSED OF WILLIAM H. MARGERISON AND ALBERT E. MARGERISON.

DESIGN FOR A TOWEL.

Application filed July 10, 1928. Serial No. 27,426. Term of patent 3½ years.

To all whom it may concern:

Be it known that I, ROMAIN DE TIRTOFF, (ERTÉ), a citizen of Russia, residing at Paris, France, have invented a new, original and ornamental Design for a Towel, of which the following is a specification, reference being had to the accompanying drawing, forming part thereof.

The figure is a perspective view of a towel showing my new design.

I claim:

The ornamental design for a towel, as shown.

ROMAIN DE TIRTOFF, (ERTÉ).
